Application October 21, 1948, Serial No. 55,794

3 Claims. (Cl. 210—1.5)

1

This invention relates to improvements in a magnetic separator and method of magnetic separation, which invention is highly desirable for use in connection with the removal of metallic particles, chips, shavings, swarf, and the like, from coolants used with cutting and grinding machines, although the invention will have other uses and purposes as will be apparent to one skilled in the art.

It is a desideratum of this invention to provide a magnetic separator simple in construction, more efficient in operation, more economical to both build and operate, and one that is easier to operate than devices of similar function heretofore known.

Another object of this invention is the provision of a magnetic separator in which the sources of magnetism are in the form of permanent magnets, rather than electromagnets, thereby eliminating numerous conduits and electrical connections, and materially lowering the cost of both manufacture and operation, and at the same time cutting the cost of maintenance by providing a device that will operate efficiently over a considerable length of time without parts becoming out of order.

Also an object of this invention is the provision of a magnetic separator embodying improved means for removing the collected magnetic particles from the collecting member, such means embodying in a preferred form of the invention a scraping device.

It is also a feature of this invention to provide a magnetic separator embodying a scraping device that, by simple mechanism, is readily adjustable toward and away from the collecting member so as to provide for most efficient operation in accordance with the character of the magnetic particles to be removed from the collecting member.

Still another feature of the invention resides in the provision of a magnetic separator embodying a scraper element for removing collected particles from the collecting member, which scraper element is fixedly mounted adjacent to and resiliently biased toward the collecting member, there being means provided to limit the effect of the biasing so that the scraper element may be maintained at a desired position relative to the collecting member.

It is also an object of this invention to provide a magnetic separator embodying permanent magnets and a collecting member, with means associated with both the magnets and collecting member to cause a bunching of the attracted

2

magnetic particles on the collecting member opposite the poles of the respective permanent magnets.

It is also an object of this invention to provide a magnetic separator embodying permanent magnets for attracting and temporarily holding particles to be separated upon a collecting member, with means provided to vary the magnetic force of the permanent magnets at desired locations.

A further feature of the invention resides in the provision of a magnetic separator including a movable collecting member carrying permanent magnets thereon, and in which separator the magnetic force of those permanent magnets is automatically reduced at the point where the collected particles are removed from the collecting member.

Another feature of the instant invention resides in the provision of a magnetic separator embodying a non-magnetic collecting member with permanent magnet means disposed on one side of that member to attract particles against the opposite side of the member, and magnetic means being provided spaced from the collecting member to shunt the flux of the permanent magnet means.

More specifically, the instant invention contemplates the provision of a magnetic separator embodying a non-magnetic rotary drum carrying permanent magnets on the outside thereof, with a fixed magnetic drum inside the rotary drum, which fixed drum acts as a shunt for the flux from the permanent magnet, fluid carrying magnetic particles to be removed being introduced between the respective drums, and the collected particles being ultimately removed by scraper means from the interior surface of the rotary non-magnetic drum.

Still a further object of the instant invention resides in a new and novel method of accomplishing magnetic separation.

While some of the more salient features, characteristics, and advantages of the instant invention have been above pointed out, others will become apparent from the following disclosures, taken in conjunction with the accompanying drawings, in which—

Figure 1 is a side elevational view of a magnetic separating apparatus embodying principles of the instant invention;

Figure 2 is a fragmentary enlarged central vertical sectional view of the structure of Fig. 1, showing certain parts in elevation;

Figure 3 is a transverse vertical sectional view

taken substantially as indicated by the line III—III of Fig. 2, looking in the direction of the arrows;

Figure 4 is a fragmentary enlarged vertical sectional view taken substantially as indicated by line IV—IV of Fig. 2, illustrating the scraper mechanism for removing collected particles from the collecting member;

Figure 5 is a fragmentary part sectional part elevational view taken from the right hand side of Fig. 4;

Figure 6 is an inside face view of the outer locking disk for holding the scraper mechanism in a desired position of adjustment; and

Figure 7 is an end view of the scraper bar, 15 showing the holding bolt in section.

As shown on the drawings:

In the illustrated embodiment of this invention there is shown a base 1 upon which a main housing 2 is seated, an auxiliary housing 3 projecting to one side of the main housing. The main housing encloses the separating apparatus itself, while the auxiliary housing 3 encloses the power unit.

Extending centrally through the main housing 2 from one end of the machine to the other is a tube or conduit 4, to which conduit a pair of legs 5 and 6 are attached to form continuations thereof, leading up to a discharge housing 7, as best seen in Fig. 1. In side the tube 4 a conveyor travels. This conveyor is of the endless type and in a preferred form may comprise a flexible chain 8 to which flights 9 are attached at spaced intervals (Fig. 2). These flights may be in the form of rubber disks reinforced on one or both sides by metallic plates. As viewed in Fig. 2, the direction of travel of the illustrated reach of the conveyor is toward the right. The conveyor is actuated by means of a motor 10 and gear reduction unit 11 mounted on top of the housing 7. Inside that housing, but not visible in the drawings, is a sprocket wheel driven from the motor 10 around which the conveyor may travel and discharge its load of separated magnetic particles out the delivery chute 12 into any suitable receptacle.

The central tube 4 and associated structure may be supported inside the housing 2 by suitable frame supports 13—13 or equivalent means. As best seen in Fig. 2, a hollow shaft 14 is disposed concentrically around the tube 4 near one end of the structure. A fluid inlet pipe 15 communicates with the interior of this hollow fixed shaft 14 through the casing or housing 2. Near the opposite end of the hollow fixed shaft 14 is a fluid discharge port 16, and both ends of the shaft are sealed around the tube 4 so that the fluid can escape nowhere else.

Suitably journaled at one end around the hollow shaft 14 and at the other end around the tube 4 is a rotary drum 17, one end of which is completely sealed by a closure disk 18, and the other end of which is closed by a disk 19 having an annular series of outlet ports 20 therein which communicate with a discharge chute 21.

It will be noted from the structure so far described that fluid containing magnetic particles to be removed may enter the pipe 15, pass through the hollow shaft 14 around the tube 4, and exit through the discharge port 16 directly into the interior of the rotary drum 17. Clear fluid then exits from the drum through the ports 20 and out the discharge chute 21, after the magnetic particles have been removed from the fluid or liquid by means to be later described.

The drum 17 is preferably of non-magnetic material and carries on its external side a plurality of longitudinal rows of permanent magnets 22, each row of magnets being held in position by a suitable supporting member 23 secured to the end walls 18 and 19 of the drum. In the illustrated instance, the magnets are shown in the form of permanent horseshoe-magnets with their respective poles in contact with the external face of the drum 17. For purposes of illustration only I have shown three such longitudinal rows of magnets disposed equidistant apart around the non-magnetic drum 17. It is to be distinctly understood, however, that any desired number of rows of magnets may be employed, and any desired number of magnets in a row may be utilized consistent with the size of the structure and the duty it is to perform.

The drum 17 may be rotated by means of a motor 24 in the auxiliary housing 3 by means of a suitable chain 25 trained over a sprocket 26 carried by the drum. During operation the rotation of the drum is continuous. Disposed centrally beneath the drum is a suitable drip pan 27 which will receive any leakage that might occur in the region of the drum and the discharge chute 21 and also receive any condensation dripping from the drum.

Inside the rotary drum is a stationary drum 28 having inwardly dished end walls 29—29. This drum is made of magnetic material. As best seen in Fig. 3, there is a discontinuity or gap as indicated at 30 in the circumferential surface of this drum 28 between the end walls. A trough-like formation is provided by means of sloping side walls 31—31 which merge with the conveyor conduit 4, the upper portion of this conduit being cut away as indicated at 32 (Fig. 2) inside the stationary drum so as to provide access to the conveyor for the magnetic particles removed from the fluid passing between the two drums.

Located directly above the discontinuity 30 in the circumferential surface of the drum 28 is a scraper mechanism, generally indicated by numeral 33 in Figs. 2 and 3, which removes collected magnetic particles, swarf, and the like, from the inside face of the rotary drum 17. This material when removed by the scraper falls into the trough-like formation in the stationary drum and drops through the opening 32 into the conveyor conduit 4 from which it is continuously removed by the action of the conveyor.

The scraper mechanism is best seen in Figs. 4, 5, 6 and 7, and includes a mounting element 34 secured to a cylindrical flange 35 on each of the end walls 29—29 of the stationary drum. A leaf spring 36 extends outwardly and upwardly from the mounting 34 and carries at its free end a clamping and supporting element 37 engaged with a pair of ears 38 depending one from each of a pair of confronting but spaced frame members 39—39 which together form a cradle for a pair of rollers 40—40, one at each end of the cradle arrangement. These rollers bear against the inside surface of the drum 17. A similar or identical mounting assembly is disposed at the opposite end of the stationary drum, and an elongated bolt 41 extends from one of these assemblies to the other, the entire length of the drum 28. This bolt carries a nut 42 at each end to effect an adjustment of the scraper element per se, now about to be described.

The scraper embodies an elongated angle-iron 43, preferably disposed with its apex substantially downwardly. To one side of this angle

iron and projecting therebeyond a scraper blade 44 is permanently attached and the upper and free edge of this blade is beveled as at 45 to provide a relatively sharp scraping edge. Secured to each end of the angle iron 43 is a disk 46 having a projecting central portion 47 and a centrally disposed elongated slot 48 therethrough. The slot 48 is of a width to freely receive the shaft 41, but of a length materially exceeding the diameter of the shaft 41, as clearly seen in Fig. 7. Another disk 49, Fig. 6, is provided with a central diametral recess or groove 50 and a central aperture 51 of a size to properly receive the shaft 41. Two disks 46 and 49 fit together by virtue of the projection 47 and the groove 50 in the manner of match-boards, and by virtue of the elongated slot 48 in the disk 46, that disk together with the angle iron 43 and scraper 44 may be adjusted relatively to the bolt 41 and the disk 49 so as to bring the edge of the scraper bar to a desired position relative to the inside surface of the rotary drum 17. As seen in Fig. 4, it is not always desirable to have the edge of the scraper 44 bearing against or actually rubbing the inside surface of the drum 17, but the scraper may effectively perform its function with a slight space between the scraping edge and the drum surface. That space may be varied as desired from zero to a material amount depending upon the nature and size of the particles, chips, or the like being separated from the fluid passing through the rotary drum. This adjustment may be easily accomplished by merely loosening the nut 42 at each end of the bolt 41 and then bodily moving the angle iron 43 upwardly or downwardly. When the nuts are again tightened by virtue of the two disks 46 and 49 at each end of the scraper, the angle iron and scraper bar will be held firmly in the adjusted position.

At the same time, it will be noted that the scraper itself is always resiliently urged toward the inner face of the drum 17 by the leaf springs 36-36 and the forceful movement effected by these springs is limited by the rollers 40-40 riding on the inner face of the drum.

As the structure is viewed in Fig. 3, and also in Fig. 4, the drum 17 rotates counterclockwise, and it will be noted from the showing in Fig. 3 that all the material released from the inside surface of the drum by the scraper will gravitate directly into the conveyor conduit.

In operation, the instant invention is extremely efficient and highly economical. By virtue of the use of permanent magnets 22 electrical connections to the rotary drum are eliminated and no current is required to establish the proper magnetism. As stated above, the fluid bearing the magnetic particles to be removed enters through the inlet 15, passes through the hollow shaft 14, and is discharged through the port 16 directly inside the rotary drum carrying the magnets. These magnets attract the magnetic particles to the inside face of the drum as it revolves, and the clean fluid may leave the drum through the port 20 in the end wall 19 and pass out the discharge chute 21. The particles magnetically held to the inner surface of the drum remain in their respective positions until contacted by the scraper bar 44 when they fall by gravity into the conveyor conduit through the trough-like formation of the stationary drum and are carried away by the conveyor. The process is a continuous one and when utilized for the clarifying of cutting or grinding machine coolant, the coolant may be kept in continuous circulation from the

machine through the separator and back to the machine.

It should be especially noted that the efficiency of operation is materially increased by virtue of the fact that the drum 17 is of non-magnetic material while the stationary drum 28 is of magnetic material. The stationary drum is disposed sufficiently closely to the rotary drum so as to act as a shunt for the flux of the magnets 22. That is, the stationary drum provides a path of low reluctance for the magnetic flux traveling from pole to pole of each magnet 22 and causes that flux to reach radially inwardly farther than it otherwise would. Consequently, the magnetic particles removed from the fluid are in effect bunched opposite the poles of the magnets 22 and are more easily removed by contact with the scraper bar.

It will therefore be noted that the magnetic particles may be collected more rapidly and in greater quantity on the inner face of the collecting member or drum 17, by virtue of the low reluctance path provided by the magnetic drum 28.

With reference again to Fig. 3 it will also be especially noted that when the collected particles arrive in the region of the scraper, they are directly opposite the discontinuity in the surface of the stationary drum 28, and that low reluctance path has been eliminated, so that the magnetic power of the magnets 22 has accordingly been reduced, permitting an easier and readier removal of the collected particles from the inner face of the drum by the scraper.

It is believed that my novel method of magnetic separation is sufficiently apparent from the foregoing as to warrant no further specific description herein.

It will be understood that certain novel features of my invention, such for example as the scraper assembly, may be employed with magnetic separators embodying electromagnets, as well as in other apparatus.

It will, of course, be understood that various details of construction may be varied through a wide range without departing from the principles of this invention and it is, therefore, not the purpose to limit the patent granted hereon otherwise than necessitated by the scope of the appended claims.

50 I claim as my invention:

1. In a magnetic separator, a rotary drum of non-magnetic material, a plurality of permanent magnets carried by the outside surface of said drum to attract metallic particles against the inside surface of said drum, means for rotating said drum, stationary magnetic drum means disposed within the interior of said rotary drum defining a shunt for said magnets, and cooperating with said rotating drum to define a thin fluid path for particle-laden fluid, a gap arranged in the surface of said stationary drum for destroying the shunt action, thereby lessening the attractive force of said magnets in a predetermined zone during rotation of said drum, a receptacle placed in said gap, and scraper means to remove attracted particles from said drum in said zone and direct them into said receptacle.

2. In a magnetic separator, a rotating outer collecting member, permanent magnetic means carried by said collecting member to attract and hold metallic particles suspended in a liquid in contact with the inside surface of said member, roller carried scraper means to remove attracted particles from the surface of said member, re-

silient means biasing said scraper means toward the surface of said collecting member, an internal stationary drum of magnetic material, said drum having a gap in its periphery at the location of the scraper, whereby said drum acts as a magnetic shunt until the magnets reach the gap and whereby the scraper removes the particles at a position of a relatively weak field and deflects them into said stationary drum, and means to establish relative movement between the collecting member and scraper means.

3. In a magnetic separator, a stationary magnetic member and a rotating non-magnetic member arranged in concentric relationship with the rotating member outside, magnets carried on the outer face of the non-magnetic member, said magnetic member acting as a shunt for the flux of said magnets, means to introduce a fluid carrying magnetic particles between said members to cause attraction of the particles to the inner face of the non-magnetic member, said magnetic member having a discontinuity in its confronting surface, scraper means located in the zone of said discontinuity to remove attracted particles, the discontinuity providing an area of reduced

5

magnetic attraction whereby the particles may readily be removed from the inner face of the non-magnetic member by the scraper.

FRANK G. FISHER.
